(57) **CLAIM**

We claim the ornamental design for a lighting device, as
shown and described.

DESCRIPTION

FIG. 1 is a side perspective view of the lighting device;
FIG. 2 is a bottom view of the lighting device;
FIG. 3 shows a top view of the lighting device;
FIG. 4 shows a side view of the lighting device from a first
side;
FIG. 5 shows a side view of the lighting device from a
second side;
FIG. 6 shows a front-on view of the lighting device; and,
FIG. 7 shows a rear-on view of the lighting device.
The broken line disclosure represents portions of the lighting
device which form no part of the claimed design.
